UNITED STATES PATENT OFFICE.

EARLE M. MORSE, OF EAST FOXBORO, MASSACHUSETTS.

PORABLE PIVOTED-LEVER CLAMP.

1,255,773.

Specification of Letters Patent.

Patented Feb. 5, 1918.

Application filed October 28, 1914. Serial No. 869,099.

To all whom it may concern:

Be it known that I, EARLE M. MORSE, a citizen of the United States, residing at East Foxboro, in the county of Norfolk and State 5 of Massachusetts, have invented certain new and useful Improvements in Portable Pivoted-Lever Clamps, of which the following is a specification.

This invention relates to wood working 10 and more specifically to portable pivoted-lever clamps.

The object of my invention is to provide a light and simple clamping device, readily portable, for use especially in foundries to 15 hold flasks or molding frames together. The rapidity and facility with which it may be clamped and unclamped upon a molding frame makes it especially desirable for this use. It is also extremely durable, and effi- 20 cient in operation.

Other objects of this invention not at this time more particularly enumerated, will be clearly understood from the detailed description and drawings forming a part of 25 this specification.

Furthermore, this invention consists in the novel arrangement and combination of parts more particularly described in the following specification and embodied in the 30 claim appended hereunto and forming a part of this application.

Referring now to the drawings which are merely illustrative of my invention Figure 1 is a side elevation of my device in opera- 35 tive position, while Fig. 2 is a cross-sectional view of the same taken on the line 2—2 of Fig. 1.

Referring further to the drawings wherein similar reference characters designate 40 similar parts throughout the respective views, 1 designates a rod having formed on one end and integral therewith, an arm 2. A U-shaped member 3 is adapted to slide forwardly and backwardly upon said rod, a 45 pin 4 being inserted through both arms of said U-shaped member above said rod. A lever 5 is pivotally mounted at 6 near the upper end and between the upright arms of said U-shaped member 3. The pivoted end 50 of the lever 5 is formed with a serrated portion 7^a thereon, that is concentrically disposed with respect to the pivot 6. Said end of the lever also has formed thereon a concaved portion 7, the extremities of which

form biting teeth, one tooth, forming the 55 terminus for one end of the serrated portion 7^a, while the other tooth projects beyond the plane of the serrated portion 7^a. When the arm 2 is placed on one side of a molding frame, the U-shaped member 3 is moved for- 60 wardly with the lever in a lowered position until the serrated portion 7^a is against the opposite side of the frame to be clamped. The lever 5 is then raised upwardly so that the extremities of the concave portion 7 on 65 the opposite end thereof is forced into contact with the side of the frame 8 thus hold- ing said frame tightly together and bring- ing lever 5 into locked relation.

The utility, adaptability, and advantages 70 of my improved form of portable pivoted-lever clamps being obviously apparent, it is unnecessary to further enlarge upon the same herein. A most essential feature of the device is the fact that the biting teeth 75 or extremities of the concaved portion 7 on the pivoted end of the lever when moved into positive engagement with the object to be clamped when the lever is raised will not permit any slackening off the clamping means 80 when the contact is shifted from the serrated portion 7^a to positive engagement by the teeth upon upward movement of said lever.

What I claim as my invention and desire 85 to secure by Letters Patent is:

In a portable lever clamp, an L-shaped bar, a frame slidably mounted on the lower arm of said bar, a lever pivotally mounted on said frame, a serrated object engaging 90 face on the pivoted end of said lever con- centrically disposed with respect to the pivot point, said serrated portion terminating at one end in a biting tooth, and an additional biting tooth on said end of the lever spaced 95 from the first mentioned tooth and project- ing beyond the plane of the serrated portion whereby the biting teeth are adapted to be moved to positive engagement with the ob- ject when the lever is swung without any 100 slack during said movement.

In testimony whereof I affix my signature in presence of two witnesses.

EARLE M. MORSE.
